HERBERT I. KOSHLAND, OF BUFFALO, NEW YORK

DESIGN FOR A DISPLAY STAND FOR JEWELRY

Application filed January 13, 1931. Serial No. 38,294. Term of patent 3½ years.

To all whom it may concern:

Be it known that I, HERBERT I. KOSHLAND, a citizen of the United States, residing at Buffalo, in the county of Erie and State of New York, have invented a new, original, and ornamental Design for a Display Stand for Jewelry, of which the following is a specification, reference being had to the accompanying drawings, forming part thereof.

In the drawings,

Fig. 1 is a perspective of a display stand for jewelry, showing my new design.

Fig. 2 is a side elevation of the display stand shown in Fig. 1, but reduced in size.

My design as shown in the accompanying drawings comprises a display stand for jewelry in the form of a letter of the alphabet, characterized by a central, enlarged, substantially circular portion for supporting an article of jewelry or the like. The central supporting portion is of material and color which will provide a suitable background for the article being displayed and, further, which will contrast effectively with the remaining parts of the letter.

I claim:

The ornamental design for a display stand for jewelry as shown and described.

HERBERT I. KOSHLAND.
